UNITED STATES PATENT OFFICE

2,498,159

WHIPSTOCK

Roy C. Gammill, Oklahoma City, Okla., assignor, by direct and mesne assignments, to Eastman Oil Well Survey Company, Dallas, Tex., and Denver, Colo., a corporation of Delaware

Application May 12, 1944, Serial No. 535,220

1 Claim. (Cl. 255—1.6)

1

This invention relates to new and useful improvements in whipstocks.

The invention relates particularly to an improvement on the whipstock shown in the patent to McVicar No. 1,970,761.

As is well known, whipstocks are in general use throughout the oil industry and are employed for the purpose of directing a drilling bit at an angle from the old well bore. The whipstock is useful in side-tracking operations, that is, offsetting the well bore from its old course and is also necessary in controlled directional drilling operations where it is desired to intentionally curve the well bore to reach a desired objective.

The usual practice has been to connect the drill bit, which is utilized with the whipstock, to the drill pipe or string by means of an ordinary drill collar which is relatively short. As exemplified by the McVicar patent, above mentioned, the drill collar or sub as it is commonly referred to extends through a collar formed at the upper end of the whipstock, and is connected thereto by a shear pin. With this arrangement the whipstock is lowered by means of the drill pipe and after drilling is complete, is removed by the pipe since the drill bit which is larger than the whipstock collar is disposed below the collar.

Experience has shown that after the whipstock is set and the connecting pin sheared to permit downward movement of the bit along the inclined face of said whipstock, said bit is guided into the formation at an angle to the old well bore. As the bit enters the formation, the sub immediately above the bit rides in the arcuate inclined face of the whipstock and its rigidity aids in maintaining the drill bit in its angular movement through the formation. So long as the sub is engaging the whipstock, the angular drilling direction is maintained because the sub is sufficiently rigid to prevent any change in such direction. However, as soon as the drilling has progressed far enough to cause the sub to clear the lower end of the whipstock, the rigidity of the sub as an aid in maintaining the angular direction of drilling is lost. It is apparent that the drill pipe or string which is several hundreds, and in many cases, thousands of feet in length has an overall flexibility or resiliency which permits said pipe to bow or flex as the pressure is applied during the drilling operation. Thus, as soon as the sub clears the lower end of the whipstock, the flexing of the drill pipe permits the drill bit to "wander" and no definite guiding of said bit is maintained. Because the sub is relatively short the positive guiding of the drill bit is

2

lost before the new angular hole has been really started and in many instances, the new hole has not been drilled beyond the wall of the old bore. Obviously the tendency of the bit is to move back toward the old well bore and therefore, as soon as the guiding action of the sub is removed due to the sub moving below the whipstock, the bit moves back toward the old bore, thereby defeating the purpose. This is particularly true when drilling in hard formations which are difficult to penetrate.

It is, therefore, desirable to increase the length of the sub or drill collar in order to obtain a guiding action until the bit has been well started in the new or offset bore so that by the time that the sub moves below the whipstock any danger of the bit to drift back into the old bore will have been eliminated. However, because the sub extends through the whipstock collar, as shown by the McVicar patent, said sub cannot be lengthened or extended upwardly without interfering with efficient operation. Because the drill bit engages the inclined face of the whipstock and is urged outwardly thereby, the sub must be short enough to clear the whipstock collar before any appreciable outward movement of the bit occurs; otherwise the sub will bind against the whipstock collar and upon rotation of the pipe and bit to perform the drilling, the friction created by the binding of the sub against the whipstock collar would cause a rotation of the whipstock to destroy its oriented position.

It is one object of the present invention to provide an improved whipstock which is so constructed that an elongate sub or guide collar may be connected to the bit, whereby an effective guiding of the whipstock to effect proper drilling of the offset bore is assured.

Another object of the invention is to provide an improved whipstock which is formed with an elongate substantially straight portion between its inclined face and the whipstock collar, said straight portion accommodating an elongate guide sub or collar which connects the drill bit to the drill pipe.

A further object of the invention is to provide a whipstock of the character described wherein the elongate guide sub moves out of and below the whipstock collar when the drill bit engages the inclined face of said whipstock whereby bending of said sub within said collar is prevented; the whipstock also including a frangible connection between the sub and the whipstock proper.

An important object is to provide a whipstock having all of the advantages of the whipstock

shown in the McVicar Patent No. 1,970,761 and in addition having means for positively guiding the drill bit in the drilling of an offset bore, whereby drifting of the bit is prevented.

The construction designed to carry out the invention will be hereinafter described together with other features of the invention.

The invention will be more readily understood from a reading of the following specification and by reference to the accompanying drawing, wherein an example of the invention is shown, and wherein:

Figure 1 is a longitudinal, vertical, sectional view of a whipstock constructed in accordance with the invention and showing the sub in connected position.

Figure 2 is a similar view, with the sub disconnected from said whipstock.

Figure 3 is an enlarged, horizontal sectional view, taken on the line 3-3 of Figure 2.

Figure 4 is an enlarged, horizontal sectional view, taken on the line 4-4 of Figure 2.

Figure 5 is a view, similar to Figure 1, illustrating the drilling of an offset bore.

In the drawings, the numeral 10 designates a whipstock which is formed of an elongate body having a generally arcuate shape in cross-section. The upper portion of the body has its wall of a constant thickness whereby the face 11 of this portion of the body is substantially straight or parallel with the longitudinal axis of the whipstock. This straight portion of the body extends from the upper end of the body to the point indicated at A in Figure 1. Below the point A, the body has a wedge shape to form an elongate inclined guide surface 12 which surface is concave due to the fact that said body is of arcuate cross-section. The extreme lower end of the body is preferably pointed or sharpened to facilitate its setting within a cement plug or within the formation, as the case may be.

A retrieving collar 13 is provided at the upper end of the whipstock body and is preferably formed integral with said body. A drill bit 14 having an outside diameter greater than the bore 15 of the collar is disposed below said collar and is connected to the lower end of an elongate sub or guide collar 16. The elongate sub is an important feature of the invention and has its upper end connected to the lower end of the drill pipe 17. As is clearly shown in Figure 1, the outer diameter of the sub is slightly smaller than the bore 15 of the whipstock so that said sub is freely movable therethrough. The drill pipe 17 is smaller in diameter than said sub.

The drill pipe, sub and bit are arranged to be connected with the whipstock body by a frangible means, such as a shear pin 18 whereby the drill pipe may be utilized to lower said whipstock within well bore B. As illustrated the shear pin extends through the wall of the whipstock body and is fastened in the body of the drill bit 14 although, of course, said pin could connect with the sub 16. When the parts are connected the extreme upper portion of the sub 16 is disposed within the collar 13 while the drill bit 14 is located a sufficient distance above the inclined guide surface which begins at point A to permit a downward movement of the bit to effect shearing of the pin 18 without wedging the bit against the wall of the well bore B. In order to permit the use of a substantially full-gage bit, the wall of the whipstock body is provided with an opening 19 for accommodating the blades 14a of the bit; however, if desired, this opening may be

omitted. It is apparent that the elongate sub 16 spaces the drill bit some distance below the whipstock collar when said bit is connected to said whipstock.

In the use of the device, the assembly is lowered into the well bore with the bit connected to the whipstock by the shear pin, the lowering being accomplished by means of the drill pipe 17. After the whipstock has been set in position, the weight of the drill pipe is imposed on the pin 18 to shear said pin and permit the drill bit, sub and pipe to move downwardly with respect to the whipstock (Figure 2). It is noted that when in a connected position the bit is spaced above the point A or above the upper end of the inclined guide surface 12, whereby the bit may move downwardly in a plane parallel to the longitudinal axis of the whipstock a distance sufficient to shear the pin before striking the wedge. It is noted that when the pin is sheared, a sudden drop in the drill pipe and bit will occur and sufficient space must be provided below said bit to prevent wedging said bit between the inclined surface 12 and the wall of the well bore.

As the drill bit is moved downwardly after disconnection from the whipstock body, said bit will engage the inclined guide surface 12 of the whipstock and will be directed outwardly into the formation at an angle with respect to the well bore B. The length of the sub 16 is such that by the time the bit engages the upper portion of the inclined guide surface, the upper end of said sub has cleared the bore 15 of the collar, as is clearly shown in Figure 2. Thus the smaller drill pipe 17 is extending through the collar 13 when drilling begins and there is no danger of a frictional engagement of the rotating pipe and collar which might be sufficient to impart a rotation to the whipstock and thereby move it from its set position. If the sub 16 were within the collar 13 when rotation was started, a frictional engagement sufficient to turn the whipstock would be set up because of the sub having a diameter which is almost equal to the diameter of the bore of said collar.

As the bit is urged downwardly along the inclined surface of the whipstock during the drilling operation, said bit is directed outwardly at an angle to the main bore B, whereby an offset or angular bore BB is formed. As soon as the upper end of the bit body clears the lower end of the whipstock the elongate sub engages the inclined guide surface of the whipstock, said sub lying within the concaved surface. The sub is of one piece and therefore has an inherent rigidity with the result that so long as it is engaging the surface 12 of the whipstock it directs the bit in its proper line of drilling and prevents the bit from tending to drift back into the main well bore.

As compared to the drill pipe which extends to the surface, the sub 16 is relatively short and does not have a tendency to flex or bend as does the long drill pipe. This rigidity is utilized to guide or direct the bit in a proper direction during the starting of the angular bore BB. The sub has a sufficient length that by the time the upper end of the sub clears the lower end of the whipstock and its guiding effectiveness is lost, the new bore BB is of sufficient depth and its lower end is sufficiently spaced from the old bore B that there is no tendency for said bit to drift back toward said bore B.

With the elongate sub 20 which is the important feature of the invention, positive guiding or directing of the bit is maintained until the new

bore has been drilled to a depth sufficient to prevent "drifting" of the bit. The actual length of the sub may be varied within limits and so long as said sub has sufficient length to assure that the new bore BB is well started the purposes of the invention will be accomplished. It might be noted that the device is particularly advantageous when drilling in hard formations although of course it may be used in any type of formation.

The foregoing description of the invention is explanatory thereof and various changes in the size, shape and materials, as well as in the details of the illustrated construction may be made, within the scope of the appended claim, without departing from the spirit of the invention.

What I claim and desire to secure by Letters Patent is:

A whipstock including, an elongate body having a collar at its upper end, the lower portion of the body being wedge-shaped to form an inclined longitudinal guide surface, the upper end of said guide surface being spaced a substantial distance from the collar and being connected to the collar by an elongate straight wall which comprises the upper portion of the body, a drill bit disposed below the collar, an elongate rigid sub connected to the drill bit, a drill pipe having the sub attached to its lower end, said drill pipe and sub being arranged to pass through the collar and means for detachably connecting the drill pipe, sub and bit assembly to the whipstock, said sub being of such length that when the drill pipe, sub and bit assembly is in attached position, the upper end of said sub is adjacent the collar and the bit is disposed contiguous to the straight wall sec-

tion of the whipstock and spaced above the inclined guide surface, detachment of the detachable means allowing the drill pipe, sub and bit to move downwardly with respect to the whipstock with the upper end of the sub moving downwardly below the collar prior to the time that the drill bit is urged a substantial distance outwardly by its engagement with the inclined guide face of the whipstock body, the elongate sub maintaining contact with the inclined surface of the body until the bit has drilled a deflected bore which is outside the confines of the original well bore, the outside diameter of said bit being greater than the bore of the whipstock collar and the straight wall section of the whipstock body having an opening for accommodating the bit blade when said bit is in its attached position, whereby the bit may be of substantially the same diameter as the well bore in which the assembly is lowered.
